STAIR CUSHION

Morris Sachs, New York, N. Y.

Application November 1, 1932. Serial No. 640,633

3 Claims. (Cl. 20—79)

This invention relates to an improvement in stair cushions or coverings, and the object of the invention is to provide a simple and inexpensive device of this character which may be easily fitted without cutting or other alteration to stairs of various dimensions; which will present a good appearance when in use and which may be easily cleaned and will resultantly be of great durability.

10 One of the objections predominant in the stair cushions and stair coverings in use at the present time is that they are required in numerous sizes to enable a proper installation to be had due to the fact that stairs vary as to width of 15 tread and sometimes as to height of the risers. The result of this is that the stair cushions either have to be made to order to properly fit the stairs for which they are intended or else a proper size must be selected from stock, which 20 requires a stock of different sizes to be maintained by the dealer. In some types of cushions employed, that portion of the cushion intended for fitment to the risers is separate from that portion intended for the stair tread. In such cases, 25 a space or crack is located between the riser and tread cushions, in which dust, dirt and germs can lodge and can not be readily removed.

30 My invention contemplates a structure in which the objections above pointed out, and others found in present day structures, are remedied and a sturdy, sanitary and long-wearing cushion results.

In the accompanying drawing, wherein the preferred embodiment of the invention is disclosed, Fig. 1 is a plan view of a stair cushion made in accordance with this invention; Fig. 2 is a sectional view on the line 2—2 of Fig. 1, looking in the direction of the arrows; Fig. 3 is a sectional view on the line 3—3 of Fig. 1, looking in 35 the direction of the arrows; Fig. 4 is a sectional view of a portion of a substantially wide step showing how the cushion is fitted thereto; and Fig. 5 is a similar view showing the application of the cushion to a narrower step.

40 The improved cushion is provided with an outer cover or facing 6 composed of a suitable fabric, such as carpeting or the like. For a certain portion of its area, the cover 6 is backed by a suitable stiffener 7 which may be of cardboard, fibre, wood, or thin metal or of any suitable material of sufficient stiffness to reinforce and lend shape to 45 that portion of the cover 7 with which it is contiguous. The edges of the stiffener 7 are secured to the cover 6 by any suitable means such as by a line of stitching indicated at 8, a suitable padding

5 indicated at 9 filling the space between the covering and the stiffener and forming a padded cushion soft to the tread. Over three of the united edges of the covering and stiffener is placed a three-sided rigid reinforcing strip 10 60 of metal which is channel-shaped in cross section and encloses the front and two side edges of the cushion.

The covering 6 is of greater size than the stiffener 7 and is thus provided with a flexible flap-like portion 12 which projects beyond the reinforcing edge piece or frame 10 so that when the cushion is placed upon the tread 11 of a step, the flap-like flexible portion 12 extends up against the riser 13 to which it is adapted to be 70 attached.

The edges of the part 2 are suitably reinforced as by a flexible binding 14 which encloses and preferably conceals a three-sided wire frame 16 serving to maintain the portion 12 in flat condition. The ends 15 of the wire frame are spaced 75 from the ends 17 of the metal reinforcing strip 10 so that the part 12 is provided with an intermediate flexible area 18 between the two frames 16 and 10 within which it may be folded to position it at substantially right angles to the padded part resting upon the tread 11 of the step.

80 From the foregoing, the manner in which the device is attached to a step will be clearly understood. The padded part of the device, enclosed and defined by the frame 10 is placed flat upon the tread 11 of the stair and is attached thereto by nails 19, screws or other fastening elements 85 extending through the perforations 20 provided at spaced distances in the frame. In case of a 90 relatively wide stair tread, a part of which is shown in Fig. 4, a portion of the flap portion 12 may be used to co-operate with the padded part to cover the tread, the fold line 21 in the device being, in such case, relatively close to the ends 95 15 of the wire frame. Where a narrower stair tread is had, a greater portion of the part 12 will be positioned against the riser 13, the fold line 22 being then nearer to the ends 17 of the metal 100 reinforcing frame 10. The part 12 of the device in contact with the riser 13 is attached thereto by staples 23 driven into the riser and embracing the wire frame 16 as indicated in Figs. 4 and 5.

105 Through the use of a stair cushion as herein described, great freedom of installation without cutting and alteration and without the formation of joints or spaces in which dust and dirt may lodge, is provided. By shifting the position of the padded tread portion of the device relative to the riser portion 12, an accommodation of the 110

article to different stairways is attained without cutting and fitting. The flexible fold-area 18 enables any required portion of the part 12 to be utilized as tread covering, and in other cases to 5 be used as riser covering.

Various changes and modifications may be made in the structure without departing from the spirit of the invention. For example, where a 10 fully flexible flap portion 12 is desired, the stiffening wire 16 may be omitted. The covering or carpeting 6 may also be composed of several joined sections if required. These and other changes may be made, all of which are considered within the scope of the invention.

15 What I claim is:—

1. A stair covering or cushion provided with a padded portion adapted to overlie the tread of a step, said portion being provided with a fabric covering, said fabric covering extending beyond 20 the padded portion and projecting up on the riser of the step, a portion of the covering located on the riser being provided with stiffening means extending about its edges, said stiffening means terminating at a distance from the padded portion 25 so that the fabric is provided with a flexible area of substantial width located between the stiffening means and the padded portion, within which the fabric covering may be folded at any desired point to increase or decrease the size of 30 the riser portion of the cushion relative to the tread portion thereof.

2. A stair covering provided with a padded portion 35 adapted to overlie the tread of a step, said

portion having a stiff reinforcing frame extending about three of its edges and provided with a fabric covering extending over the padded portion and projecting out of the frame and adapted to project up on the riser of the step, the portion 80 of the covering projecting up on the riser having its edges reinforced with a flexible binding, a stiffening wire located in said binding, the ends of 85 said wire being spaced at a distance from the ends of the reinforcing frame, whereby a flexible area is located in the fabric covering between the frame and wire within which the covering may be folded at any selected point to regulate the relative sizes 90 of the tread portion and riser portion of the covering.

3. A stair covering for attachment to the tread and riser of a step, said covering having a stiffened, padded portion adapted to overlie the tread of a step, said portion having a fabric covering, one edge of said covering extending out beyond 95 one edge of the stiffened, padded portion and adapted to project up against the riser of a step, a reinforcement for the projecting part of said covering, said reinforcement having its inner end terminating at a distance from the edge of the 100 stiffened portion so that a freely flexible area is provided in the fabric covering between the stiffened portion and the reinforced portion and the sizes of these two portions relative to one another 105 can be altered by folding the covering at a selected point within its flexible area.
